RADIATOR BACK FLUSH AND CLEANING
BOOTH

Earle Grant Webb, Bellevue, Nebr., assignor, by
mesne assignments, to Inland Manufacturing
Company, Omaha, Nebr., a corporation of
Nebraska

Application November 9, 1946, Serial No. 709,078

2 Claims. (Cl. 134—102)

1

This invention relates to a radiator back-flush and cleaning booth and particularly to such a device for use in garages and repair stations for repairing and cleaning the radiators of internal combustion engines, such as used in automobiles.

After an automobile radiator has been boiled in a cleaning vat, which generally contains a caustic or some other cleaning chemical, it is necessary to spray the outside of the radiator with a strong stream of water to remove external foreign matter from the fins of the radiator. It is also necessary to back-flush the radiator to remove accumulations of foreign matter from the interior of the radiator which have been previously loosened in the boiling vat.

Heretofore this series of operations has required that the radiator be moved from one position to another to accomplish both cleaning steps and also has been extremely messy in that the water from both the external cleaning and the back-flushing has been permitted to run over the floor, generally to a floor drain. Furthermore, the water was likely to splash over the surroundings and operator during the cleaning and flushing operation.

It is an object of the present invention to provide a single cabinet which is fully enclosed when back-flushing is taking place and which is partially enclosed when external cleaning is being effected.

It is another object of the invention to substantially prevent any splashing of water from the radiator cleaning operations on the operator and the surroundings.

It is a further object of the invention to afford more rapid external washing and internal back-flushing than is possible with existing equipment.

It is also an object of the invention to provide a machine wherein both external and internal cleaning are performed in the same cabinet and in the same position, thus eliminating the necessity of moving the radiator.

It is an additional object of the invention to provide a novel radiator support in a cleaning cabinet to maintain the radiator in the most convenient position.

It is a further object of the invention to provide a construction by which the back-flushing operation may be observed while the back-flushing process is being carried on, even though the cabinet is completely closed at this time.

It is another object of the invention to provide a cleaning and back-flush cabinet for radiators which is provided with a drain so that all water from these operations is drained directly from the cabinet to a suitable outlet.

Another object of the invention is to provide for complete control of the operations for cleaning and back-flushing a radiator from the front of the cabinet and also to provide for control of

2

the back-flushing operation from the front of the cabinet when the cabinet doors are closed.

It is still another object of the invention to provide improved back-flushing of the radiator to be cleaned and, more specifically, to insure that a sufficient column of water under high pressure is forced rapidly through the radiator.

It is also an object of the invention to provide complete external washing and back-flushing apparatus in a single cabinet, including the necessary machinery for effecting these operations.

It is still a further object of the invention to construct the bottom of a booth for cleaning radiators in such a manner that no water may run out the front thereof.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a front perspective view of the radiator cleaning and back-flush cabinet shown with the doors thereof closed.

Figure 2 is a front perspective view of the cabinet or booth with the doors open and the back-flush hose connected to a radiator.

Figure 3 is a front perspective view of the booth with the doors open, showing the back-flush hose and the external cleaning hose in the position in which they are placed when not in use.

Figure 4 is a front perspective view of the cabinet or booth with the doors open and illustrates the external cleaning of a radiator.

Figure 5 is a back elevational view of the cabinet and mechanism associated therewith.

Figure 6 is a sectional view of the cabinet and mechanism taken on line 6—6 of Figure 5; and

Figure 7 is a sectional view of the cabinet and mechanism taken on line 7—7 of Figure 5.

Referring specifically to the drawings for a detailed description of the invention, numeral 1 designates generally an enclosed cabinet, having side walls 2, a top wall 3, a bottom wall 4, and a pair of doors 5 hinged to the front of the cabinet and provided with a latch 6. Transparent windows 7 are provided at the upper portions of the doors 5 in such position that they are at the eye level of the average operator.

A vertical wall 8 is formed interiorly of the cabinet and extends upwardly from the bottom wall 4 a short distance. An upwardly sloping wall 9 extends from the wall 8 and connects with a vertical wall 10. The walls 8, 9 and 10 form the rear wall of the cabinet. A flange 11 is disposed at the juncture between the walls 8 and 9. A radiator 12 is supported with its bottom on the wall 9 and its top resting against wall 10, the flange 11 preventing the radiator from slipping

off the wall 9. The radiator is preferably disposed with the part that normally faces the engine facing the front of the cabinet.

A hose 13 for external cleaning of the radiator 12 is provided with a nozzle 14 and extends from an aperture 15 in the short vertical wall 8. The radiator 12 includes external fins 12a and water passages 12b. A back-flush hose 16 is connected to the radiator at a bottom connection 51 by a clamp 17 and the hose 16 extends from an aperture 18 in the short vertical wall 8. The construction of the clamp 17 is fully described and claimed in my issued U. S. Letters Patent No. 2,526,055, dated October 17, 1950, for Clamp Device and no further description thereof is deemed necessary except to state that the clamp tightly connects hose 16 and outlet 51.

Brackets 19 and 21 are provided on side wall 2 adjacent hose 16, in order to support the hose in its operative position, such as shown in Figure 2, and in its stored position, such as shown in Figures 3 and 6. A similar clamp 22 is provided on the other side wall 2 to support the hose 13 in its stored position, as shown in Figure 2. A scabbard 23, which is open at its bottom, is provided on the side wall 2 adjacent hose 13, so that the operator need not stop the flow of liquid from the hose 13 if he wishes to use his hands for some other purpose but is enabled to place the nozzle 14 in the scabbard 23. A waterproof light 20 is disposed near the top of the cabinet for a purpose hereinafter described.

A city water inlet conduit 24 conveys water to the cabinet and part of the water flows through a branch conduit 25 having a shut-off valve 26 therein, which branch conduit 25 is connected to a water pump 27 driven by a motor 28. The pump 27 and motor 28 are bolted to the bottom 4 of the cabinet and are shielded by vertical flanges 30 at the rear of the cabinet. A conduit 29 connects the outlet of the pump 27 with the hose 13. A control rod 31 for operating valve 26 extends through the rear wall 10 of the cabinet and is supported by an ear 32 adjacent the front of the cabinet. A hand wheel 33 is secured to the outer end of rod 31 adjacent the front of the cabinet and in an accessible position for the operator when the doors 5 are opened.

Another branch line 34 extends from the conduit 24 and has a back check valve 35 and an off-and-on control valve 36 therein. A compressed air line 37 having a valve 38 therein is connected to the branch line 34 adjacent the bottom thereof at the back of the cabinet 1.

A control rod 39 for operating valve 36 in water line 34 extends through the back of the cabinet 1 and is supported at the front thereof by a flange 41. A hand-wheel 42 is disposed at the end of the rod 41 adjacent the front of the cabinet in an accessible position for the operator when the doors 5 are open.

A control rod 43 for operating the valve 38 in compressed air line 37 also extends through the back of cabinet 1 and is supported at the front thereof by a flange 44. The rod 43 is provided with a push-button 45 located at the front of the cabinet in such position that it extends through an aperture 46 in one of the doors 5 when the doors are closed.

A conduit 47 connects the conduit 34 with the backflush hose 16 and it will be noted that the compressed air line 37 enters the water-line 34 at the juncture of line 34 and conduit 47, thus insuring a substantial column of water between 75

the entrance of the compressed air in line 37 and the end of hose 16.

A drain hole 48 is provided in the bottom wall 4 of the cabinet and an upturned flange 49 is provided at the front of the bottom wall 4 to prevent water from running out the front of the cabinet. An inturned flange 50 is also provided on the top wall 3 of the cabinet to prevent any water which splashes on the top wall from escaping from the cabinet.

Operation

In operating the above apparatus, city water is admitted to the conduit 24 and it is assumed that both the water valves 26 and 36, as well as the compressed air valve 38, are closed. A radiator 12, which has previously been boiled in a boiling vat, is positioned as shown in Figures 2 and 4 and the first operation is to clean foreign matter from the external fins of the radiator. For this purpose, the hand-wheel 33 is turned to open valve 26 and a switch 54 is closed, thus starting motor 28 and pump 27. Switch 54 is controlled by a rod 55 which extends to a position adjacent the front of the cabinet and accessible when the doors 5 are opened.

Water is therefore delivered through conduit 25, water pump 27, conduit 29 and hose 13, and emerges from the nozzle 14 in a strong, fine stream. The operator directs the stream against the external portions of the radiator 12, as shown in Figure 4, to completely remove foreign matter from the fins of the radiator.

After the external cleaning is completed, the operator may either close valve 26 by turning hand-wheel 33, or may elect to leave the valve open and place the nozzle 14 of the hose 13 in the scabbard 23. It will be clear that any water emerging from the nozzle 14 will fall to the bottom of the cabinet and will drain from aperture 48, the flange 49 preventing water from running out of the front of the cabinet. Furthermore, the radiator is substantially enclosed in the cabinet during this process and very little splashing of the operator or the surroundings results.

The operator then connects the back-flush hose 16 to the conduit 51 of radiator 12 by utilizing clamp 17. The radiator is provided with a tube connection 52 and with a fill conduit 53, which is blocked during the operation about to be described. The operator then opens valve 36 by turning hand-wheel 42 and water flows through the branch conduit 34, conduit 47 and hose 16; thence through the radiator from bottom connection 51 and out of tube connection 52. However, only city water pressure is available at this time and the flow is rather slow through the small passages of radiator 12, which water emerging from the outlet 52 falls to the bottom of the cabinet and is removed through drain 48.

In order to effectively back-flush the radiator, that is, force water in the reverse direction from the normal flow when the radiator is installed in an automobile, the doors 5 are closed and the operator pushes button 46 to open compressed air valve 38. Compressed air at a pressure of preferably about 150 pounds per square inch flows through the compressed air conduit 37 and admits full air line pressure behind the water stream. This forces the water rapidly through the radiator from the inlet 51 to the outlet 52, which water is under considerable pressure and effectively removes any foreign matter in the passages of the radiator.

When the operator pushes the button 46, he

may observe the operation through the windows 7, since the light 20 adequately permits him to do so. The color of the water emerging from the outlet 52 during back-flushing is an indication of when the process is complete. If the color of the water shows the operator that further back-flushing is necessary, he periodically pushes the button 45 to provide a series of pressure impulses to the water passing through the radiator 12. When back-flushing is complete, the operator opens the doors 5 and shuts off valve 38.

The back check valve 35 prevents the water in line 34 under pressure from entering water line 25 and pump 27.

From the foregoing, it will be apparent that we have provided an improved cabinet and mechanism for external cleaning and back-flushing of radiators which permit rapid cleaning of the radiators, both externally and internally, and prevents messy splashing of water on the surroundings and on the operator. Furthermore, the operator is enabled to visually observe the back-flushing process and to determine the condition of the radiator and control such process, even though the doors of the cabinet are closed.

Some changes may be made in the construction and arrangement of the parts of my radiator back-flush and cleaning booth without departing from the real spirit and purpose of my invention, and it is my intention to cover by my claims 30 any modified forms of structure or use of mechanical equivalents which may be reasonably included within their scope without sacrificing any of the advantages thereof.

I claim as my invention:

1. A device for cleaning the radiator of an internal combustion engine, said radiator comprising upper and lower liquid connections, external fins and internal passages, said device comprising a cabinet for supporting said radiator interiorly thereof, said cabinet comprising top, bottom and side walls together with a vertical wall extending between the front and rear of said cabinet and having a bottom portion offset forwardly to define a forwardly sloping support 45 for said radiator in erect position above said

bottom wall, said vertical wall subdividing said cabinet into front and rear compartments open, respectively, to the front and rear of said cabinet, said rear compartment having a forward portion extending below a rear portion of said forward compartment, said bottom wall having an upstanding front flange and being apertured between said flange and said vertical wall, movable closure means for said front compartment, a first conduit for cleaning liquid extending in said rear compartment through said offset vertical wall portion, a second flexible conduit in said front compartment connected to said first conduit, means for removably connecting said second conduit to a radiator liquid connection, a check valve in said first conduit permitting fluid flow therethrough only into said second conduit, a conduit for compressed air in said rear compartment connected to said first liquid conduit, and means accessible from the front of said cabinet for controlling the flow of fluid through said first conduit and through said air conduit.

2. A device according to claim 1 having means for controlling the flow of fluid through said air conduit extending through said closure means and operable with said closure means in front compartment closing position.
